(57) **CLAIM**

The ornamental design for a pork chop pet treat, as shown and described.

DESCRIPTION

FIG. 1 is front, top, right side perspective view of a first embodiment of a pork chop pet treat according to the new design;

FIG. 2 is a front, bottom, left side perspective view of the embodiment of FIG. 1;

FIG. 3 is a front view of the embodiment of FIG. 1;

FIG. 4 is a back view of the embodiment of FIG. 1;

FIG. 5 is a left side elevation view of the embodiment of FIG. 1;

FIG. 6 is a right side elevation view of the embodiment of FIG. 1;

FIG. 7 is a top plan view of the embodiment of FIG. 1;

FIG. 8 is bottom plan view of the embodiment of FIG. 1;

FIG. 9 is front, top, right side perspective view of a second embodiment of a pork chop pet treat according to the new design;

FIG. 10 is a front, bottom, left side perspective view of the embodiment of FIG. 9;

FIG. 11 is a front view of the embodiment of FIG. 9;

FIG. 12 is a back view of the embodiment of FIG. 9;

FIG. 13 is a left side elevation view of the embodiment of FIG. 9;

FIG. 14 is a right side elevation view of the embodiment of FIG. 9;

FIG. 15 is a top plan view of the embodiment of FIG. 9;

FIG. 16 is bottom plan view of the embodiment of FIG. 9; FIG. 17 is front, top, right side perspective view of a third embodiment of a pork chop pet treat according to the new design;

FIG. 18 is a front, bottom, left side perspective view of the embodiment of FIG. 17;

FIG. 19 is a front view of the embodiment of FIG. 17;

FIG. 20 is a back view of the embodiment of FIG. 17;

FIG. 21 is a left side elevation view of the embodiment of FIG. 17;

(Continued)

FIG. 22 is a right side elevation view of the embodiment of FIG. 17;
 FIG. 23 is a top plan view of the embodiment of FIG. 17;
 FIG. 24 is bottom plan view of the embodiment of FIG. 17;
 FIG. 25 is a front, top, right side perspective view of a fourth embodiment of a pork chop pet treat according to the new design;
 FIG. 26 is a front, bottom, left side perspective view of the embodiment of FIG. 25;
 FIG. 27 is a front view of the embodiment of FIG. 25;
 FIG. 28 is a back view of the embodiment of FIG. 25;
 FIG. 29 is a left side elevation view of the embodiment of FIG. 25;
 FIG. 30 is a right side elevation view of the embodiment of FIG. 25;
 FIG. 31 is a top plan view of the embodiment of FIG. 25;
 FIG. 32 is bottom plan view of the embodiment of FIG. 25;
 FIG. 33 is a front, top, right side perspective view of a fifth embodiment of a pork chop pet treat according to the new design;
 FIG. 34 is a front, bottom, left side perspective view of the embodiment of FIG. 33;
 FIG. 35 is a front view of the embodiment of FIG. 33;
 FIG. 36 is a back view of the embodiment of FIG. 33;
 FIG. 37 is a left side elevation view of the embodiment of FIG. 33;
 FIG. 38 is a right side elevation view of the embodiment of FIG. 33;
 FIG. 39 is a top plan view of the embodiment of FIG. 33; and,
 FIG. 40 is bottom plan view of the embodiment of FIG. 33. The broken lines in FIGS. 1-4, 25-28 and 33-36 illustrate portions of the pork chop pet treat that form no part of the claimed design.
